FALLER BAR SYNCHRONIZING
AND CROSS-DRIVE

Richard G. Denton, Jr., Cleveland, Ohio, assignor
to The Warner & Swasey Company, Cleveland,
Ohio, a corporation of Ohio

Application October 4, 1949, Serial No. 119,550

10 Claims. (Cl. 19—129)

1
This invention relates to gill boxes, and more particularly to timing mechanism for the faller bar screws of the rectilinear motion type machines.

The gill boxes of the type to which the invention relates comprise upper and lower sets of faller bars and their driving screws. Each set in turn comprises right and left hand pairs of driving screws geared together, and the right and left hand upper pairs are geared respectively to the right and left hand lower pairs. Finally, a common drive in the form of a cross-shaft and bevel gear assembly is provided for all the screws. It is important that the screws in geared pairs be individually timed with respect to one another so that the screws and S-cams will properly transfer faller bars from one screw to the other. It is also important that the upper and lower pairs be aligned so that the teeth of the upper and lower sets of faller bars alternate. Finally, it is necessary that the right and left hand sets of screws be relatively adjusted so that the faller bars are disposed in their proper transverse relationship.

In view of the close spacing of the faller bars, a refined adjustment is desirable, which adjustment should be refined enough so that back lash after normal wear will not bring the faller bars into engagement in a binding or dangerous manner. Various means have been proposed for adjusting the faller bars, but they have either involved devices such as serrated teeth which do not provide a fine adjustment or devices embodying spaced holes with pin connections wherein adjacent holes are of different angular spacings. With the latter arrangement, the adjustment can only be perfected after considerable trial and error and requires an unduly long time on the part of workmen to assemble the unit.

It is an object of the invention to provide a readily selected, precise and refined adjustment between each pair of screws and between upper and lower pairs of screws. This is accomplished by forming separable gear and hub elements at the screws which include equiangularly spaced recesses and a driving pin. The spacing of the recesses is selected so that there is a small difference between the recess spacing and the spacing of two gear teeth. This difference and the number of recesses are arranged so that by selectively connecting the pin with the recesses, an adjustment is obtained whereby the angular spacing of adjacent gear teeth is divided into equal parts, the number of which equals the number of recesses. The aforesaid division parts

5 of a single tooth angle may in turn be selectively divided into equal subparts by providing another set of equidistant recesses and a driving pin in the other of two meshed gears, the latter recesses being spaced differently from the spacing of the recesses in the first gear. I have found, for example, that with relatively coarse gears having 16 teeth, and with relatively heavy driving pins, I can obtain a relatively fine minimum adjustment, namely an adjustment in the neighborhood of 30° of arc. This is accomplished with a structure that is simple, strong, and easily fabricated. I contemplate providing a similar refined adjustment between each upper and lower set of meshed gears.

20 A further object resides in the provision of a readily adjustable cross-shaft drive between the right and left hand sets of screws. This may take the form of a hub portion for one of the bevel gears that is fixed to the shaft and has a radial arm received in a slot in the gear portion, the slot being wider than the arm. By taking up and loosening opposed screws engaging the hub arm, a very precise and firmly-maintained adjustment may be provided with all gears in mesh, to transversely align the faller bars.

25 It is a feature of this adjustment that one of the hub members may be axially split to facilitate assembly of the parts in the framework of the apparatus.

30 The manner in which these and other advantages and objects may be attained will be apparent from the following detailed description of a preferred form of the invention.

35 In the drawings:

Fig. 1 is a simplified front elevation of a gill box showing portion of the gearing;

Fig. 2 is a fragmental section through one set of faller bars, screws and gearing;

40 Fig. 3 is a plan view of the cross-drive shaft;

Fig. 4 is a section to one of the cross-drive adjustment gears taken on 4—4 of Fig. 3;

45 Fig. 5 is an enlarged end view of a pair of faller bar gears showing the angular relationship partial section through the gearing of an upper pair of faller bar screws; and

Fig. 6 is a section taken on 6—6 of Fig. 5.

As seen in Fig. 1, tandem gill boxes G may be provided, each including a frame work indicated generally at 10, it being understood that in the broader aspects of the invention, a single gill box may be employed. The gill box shown in Figs. 1 and 2 is of the type that employs movable faller bars, advanced and returned by a helical screw. The arrangement of faller bars shown is one well

known in the art wherein upper and lower sets of bars are provided, each set being actuated by right and left hand pairs of faller bar screws, the screws in each pair being geared together. For example, as best seen in Fig. 1, the upper set of faller bar drive includes right and left pairs of upper screw shafts 11 and lower screw shafts 12, whereas the lower set includes right and left pairs of upper screw shafts 13 and lower screw shafts 14. The aforesaid shafts carry the advance and return screws, as is well known in the art, for advancing and returning the upper set of faller bars F and the lower set of faller bars F¹.

The gearing and adjustment means between each of the pairs of faller bars is preferably of the same construction so that the arrangement for only one pair need be described. The construction, as best seen in Figs. 5 and 6, includes the upper shaft 11 which has a hub element 20 keyed thereto at as 20a and an associated gear element 21. A number of adjusting holes 22 are bored in the upper gear 21 in accordance with a plan which will be explained in detail presently.

A drive pin 23 is fixed by any suitable expedient in hub 20, and may be selectively fitted into any of the bores 22 in the gear element. The gear element 21 is detachably mounted on shaft 11 by means of a bolt 24, threaded into a tapped hole 26, and cooperating with the washer 27 to retain the gear in position. A similar construction is mounted on shaft 12, which includes a hub element 30 keyed to the shaft as at 30a, a lower gear element 31 in mesh with the upper gear 21 and provided with a series of bores 32 receiving a pin 33 fixed in hub element 30. The gearing arrangement just described is repeated at each pair of faller bar screws.

In order to gear together the upper and lower pairs of screws, an interconnect gear 41, which is formed with a series of bores 42 is retained on an extension of shaft 12 by means of a bolt 24 and washer 27. In order to establish a driving connection from gear 41, a pin 43 is mounted in gear 31 and slidably extends into any one of the series of apertures 42 formed in the gear 41. As seen in Fig. 1, a lower interconnect gear 51 is mounted on an extension of shaft 13 and drives the lower faller bar gear 24 by means of a pin 53 adjustable in any of a series of bores 52 formed in the gear 51.

The gearing and driving connections just described, although they are of the simple, rugged construction, are arranged to provide a very refined or precise adjustment between the various meshed gears. The principles of this construction may be best understood with reference to Fig. 5 wherein the pair of gears 21 and 31 is shown, it being understood that the angular values indicated are merely illustrative of a preferred embodiment and not determinative of the scope of the invention. In the construction shown, the two gears are 16-tooth gears so that the adjustment obtainable by shifting one tooth, is 22½°, which is entirely too coarse an adjustment.

It will be noted that there are seven bores 22 in the upper gear 21, adjacent of these bores being spaced at an angle of 48° 13'. This spacing gives ample room for a large, heavy-duty pin. It will be noted that there is a differential angle of 3° 13' between this spacing of adjacent bores 22 and a pair of teeth of the gear. Thus, by using a pin-to-tooth adjustment with the upper gear anywhere from 1 to 6 increments of 3° 13' angles may be introduced between the upper and lower

gears. For example, if the upper gear is removed by removing gear 41 and bolt 24 and the upper gear is advanced so that the pin 23 rests in the next bore 22 and, if at the same time, the lower gear 31 and its shaft are turned in the opposite direction by two teeth when the gears are released, the faller bar screws will be offset 3° 13'. A similar construction is provided for the lower gear 31 except that here the bores 32 are six in number instead of seven and they are separated by an angle of 48° 45' giving a differential angle relative to the separation of two gear teeth of 3° 45'. These adjustments are set out in the table below:

Pin to tooth adjustment

7 hole gear:

Unit differential angle 3° 13'
Total adjustment $6 \times 3^\circ 13' = 19^\circ 18'$
Subtract from one tooth $22^\circ 30' - 19^\circ 18' = 3^\circ 12'$

6 hole gear:

Unit differential angle 3° 45'
Total adjustment $5 \times 3^\circ 45' = 18^\circ 45'$
Subtract from one tooth $22^\circ 30' - 18^\circ 45' = 3^\circ 45'$

Pin to pin adjustment

30 Unit differential angle = 48° 45' - 48° 13' = 32'
Total adjustment = $5 \times 32' = 2^\circ 40'$
Subtract above from unit differential angle of 7 hole gear $3^\circ 13' - 2^\circ 40' = 33'$

35 As shown by the aforesaid table, a pin-to-tooth adjustment may be effected with the lower gear which divides each tooth into six equal angular segments.

The angles between each of the sets of bores 22 and 32, respectively, are selected so that a pin-to-pin adjustment may be made which divides the unit differential angle obtainable by the pin-to-tooth adjustment of the gear 21 into six subdivisions. As seen from the table, this subdifferential angle is only 32' of arc which provides a very precise or refined adjustment. This small differential angle is obtainable by unmeshing both gears and advancing them simultaneously by an equal number of pin apertures. The adjustments just described, are uniform and progressive, and the workman always knows where he stands in performing them. The assembler can easily select increments from either of the pin-to-tooth differentials and then refine those incremental adjustments by selecting any desired number of the pin-to-pin adjustment increments.

55 The adjustment of the interconnect gears, which gear together the upper and lower pairs of faller bars, is of equal importance to that just described because it is necessary that the faller bars alternate instead of coming together during the draft stroke. To this end, the interconnect gears 41 and 51 are provided with adjustments like those just described for the pairs of screw shafts. For example, these gears might be 19-

65 tooth gears and one may have six bores 42 spaced by angle 41° 3'; the other having seven bores 52 with a spacing of 40° 30'. This gives pin-to-tooth differential angles and pin-to-pin differential angles that are somewhat smaller than those obtainable in the construction first described. The adjustment of these gears is of course performed after the individual faller bar screws are aligned together.

70 Means are provided for a fine vernier adjustment between the right and left sets of faller

bars with the various gears in mesh. Lower shafts 14 are extended to receive bevel gears 60 keyed to the shaft 61 and retained by fastener 62. A bevel gear 63 is mounted on the cross-drive shaft 64 for meshing with one of the aforesaid bevel gears 60. Shaft 64 is held in place by bearing caps 66 and turns in a ball bearing 67. The other bevel gear 60 is driven by an adjustable or vernier gear indicated generally at A. Gear A includes a gear element 70 and a split hub element composed of sections 71 and 71a, section 71 being keyed to the shaft as at 72 and the two sections clamped to the shaft by means of screws 73. Section 71a of the hub element is provided with an arm 74 which extends freely into a notch 75 formed in the gear element 70. In order to adjustably connect the hub and the gear elements, opposed set screws 76 are threaded into the gear element 70 so as to engage opposite sides of the hub element arm 74. The clearance between the arm 74 and the notch 75 should be substantially equal to the angular space between corresponding points on adjacent teeth on the bevel gear 70. With this construction, gear 63 on shaft 64 may be meshed with gear 60 in the faller bar train and gear 60 in the other or righthand train of gears turned to approximate alignment, which alignment is close enough so that error is no greater than the angle represented by one tooth of the bevel gear.

The gear element 70 which is mounted on the shaft but clear of gear 60 may now be slid along the shaft to mesh with gear 60 and the split hub elements applied and clamped. A very fine and precise vernier adjustment is then obtainable by manipulation of screws 76 so that the right and left hand faller bar screws may be precisely aligned with all gears.

Thus, it can be seen with the construction described, each pair of faller bar screws may be aligned together within a tolerance that is much less than the amount of lost motion or back lash normally encountered. In the interconnection, the upper and lower pairs of screws may be likewise precisely aligned. No fine serrated teeth are required, the adjustment being simple to machine and of strong construction. Yet, the clearance may be adjusted by increments as fine as 30' of angle or less, and this is done without trial and error because the various increments of adjustment may be regularly and progressively selected, according to a simple pattern or plan.

Finally, by use of the vernier bevel gear and hub elements, the right and left pairs of geared screws may be aligned for transverse orientation of the faller bars, the only requirement being that the gears be meshed accurately enough so that the adjustment falls within the range of the vernier screw adjustment.

Having completed the detailed description of the preferred embodiment of the invention, it will be apparent that various modifications thereof may be made without departing from the essence of the invention as defined in the appended claims.

What is claimed is:

1. In a gill box, an upper set of faller bar translating means, said upper set comprising right and left pairs of lead and return screws, first gear means between each pair of screws, said first gear means including adjustment means for providing precise adjustment between the individual screws of each pair, a similarly arranged lower set of faller bar translating means including adjustment means between each pair of screws, second gear means for gearing together the right

upper and lower pairs of screws and the left upper and lower pairs of screws, said second gear means comprising adjustment means for providing precise adjustment between the associated 5 upper and lower pairs of screws, and third gear means for gearing together said right and left pairs of screws, said third gear means comprising adjustment means for providing precise adjustment between said right and left pairs of 10 screws with all of said means in mesh.

2. In a gill box, an upper set of faller bar translating means, said upper set comprising right and left pairs of lead and return screws, first gear means between each pair of screws, said first gear means including differential adjustment means for providing precise adjustment between the individual screws of each pair, said differential adjustment means comprising a connection between each gear and its screw that 15 provides for mounting the gear in a plurality of equally-spaced angular positions on the screw, the spacing of the angular positions of one of the pair of meshed gears being greater than that of the other, a similarly arranged lower set of faller bar translating means including adjustment means between each pair of screws, second gear means for gearing together the right upper and lower pairs of screws and the left upper and lower pairs of screws, said second gear means comprising 20 adjustment means for providing precise adjustment between the associated pairs of screws, and third gear means for gearing together said right and left pairs of screws, said third gear means comprising adjustment means for providing precise adjustment between said right and left pairs of screws with all of said gear means in mesh.

3. In a gill box, an upper set of faller bar translating means, said upper set comprising right and left pairs of lead and return screws, first gear means between each pair of screws, said first gear means including adjustment means for providing precise adjustment between the individual screws of each pair, a similarly arranged lower set of faller bar translating means including adjustment means between each pair of screws, second gear means for gearing together the right upper and lower pairs of screws and the left upper and lower pairs of screws, said second gear means comprising adjustment means for providing precise adjustment between the associated upper and lower pairs of screws, one of said left screws and the right screw horizontally aligned therewith each including a shaft extension carrying first bevel gears, a cross-shaft carrying bevel gears for meshing with said first bevel gears, one of said bevel gears including adjustment means for providing precise adjustment between said right and left pairs of screws with all of said gear means in mesh.

4. In a gill box, an upper set of faller bar translating means, said upper set comprising right and left pairs of lead and return screws, first gear means between each pair of screws, said first gear means including differential adjustment means for providing precise adjustment between the individual screws of each pair, said differential adjustment means comprising a connection between each gear and its screw that provides for mounting the gear in a plurality of equally-spaced angular positions on the screw, the spacing of the angular positions of one of the pair of meshed gears being greater than that of the other, a similarly arranged lower set of faller bar translating means including adjustment

means between each pair of screws, second gear means for gearing together the right upper and lower pairs of screws and the left upper and lower pairs of screws, said second gear means comprising adjustment means for providing precise adjustment between the associated pairs of screws, and third gear means for gearing together said right and left pairs of screws, said third gear means comprising adjustment means for providing precise adjustment between said right and left pairs of screws with all of said gear means in mesh.

5. In a gill box, an upper set of faller bar translating means, said upper set comprising right and left pairs of lead and return screws, first gear means between each pair of screws, said first gear means including first differential adjustment means for providing precise adjustment between the screws of each pair, said first differential adjustment means comprising a connection between each gear and its screw that provides for mounting the gear in a plurality of equally-spaced angular positions on the screw, the spacing of the angular positions of one of the pair of meshed gears being greater than that of the other, a similarly arranged lower set of faller bar translating means including adjustment means between each pair of screws, second gear means for gearing together the right upper and lower pairs of screws and the left upper and lower pairs of screws, said second gear means comprising second differential adjustment means comprising a connection between each gear and its screw that provides for mounting the gear in a plurality of equally-spaced angular positions on the screw, the spacing of the angular positions of one of the pair of meshed gears being greater than that of the other, and third gear means for gearing together said right and left pairs of screws, said third gear means comprising adjustment means for providing precise adjustment between said right and left pairs of screws with all of said gear means in mesh.

6. In a gill box, an upper set of faller bar translating means, said upper set comprising right and left pairs of lead and return screws, first gear means between each pair of screws, said first gear means including adjustment means for providing precise adjustment between the individual screws of each pair, a similarly arranged lower set of faller bar translating means including adjustment means between each pair of screws, second gear means for gearing together the right upper and lower pairs of screws and the left upper and lower pairs of screws, said second gear means comprising adjustment means for providing precise adjustment between the associated pairs of screws, one of said left screws and the right screw horizontally aligned therewith each including a shaft extension carrying a first bevel gear, a cross-shaft carrying bevel gears for meshing with said first bevel gears, one of said bevel gears including a hub portion fixed to its shaft and having a radial arm and a gear portion rotatable on the shaft and having opposed adjusting screws engaging said arm for providing precise adjustment between said right and left pairs of screws with all of said gear means in mesh.

7. In a gill box, an upper set of faller bar translating means, said upper set comprising right and left pairs of lead and return screws, first gear means between each pair of screws, said first gear means including adjustment means for providing precise adjustment between the individual screws of each pair, a similarly arranged lower set of faller bar translating means including adjustment means between each pair of screws, second gear means for gearing together the right upper and lower pairs of screws and the left upper and lower pairs, said second gear means comprising adjustment means for providing precise adjustment between the associated pairs of screws, one of said left screws and the right screw horizontally aligned therewith each including a shaft extension carrying a first bevel gear, a cross-shaft carrying bevel gears for meshing with said first bevel gears, one of said bevel gears including a hub portion fixed to its shaft and having a radial arm and a gear portion rotatable on the shaft and having opposed adjusting screws engaging said arm for providing precise adjustment between said right and left pairs of screws with all of said gear means in mesh.

vidual screws of each pair, a similarly arranged lower set of faller bar translating means including adjustment means between each pair of screws, second gear means for gearing together the right upper and lower pairs of screws and the left upper and lower pairs, said second gear means comprising adjustment means for providing precise adjustment between the associated pairs of screws, one of said left screws and the right screw horizontally aligned therewith each including a shaft extension carrying a first bevel gear, a cross-shaft carrying bevel gears for meshing with said first bevel gears, the inner bevel gear on said cross-shaft including a hub portion clamped to the shaft and having a radial arm and a gear portion rotatable on the shaft and having opposed adjusting screws engaging said arm for providing precise adjustment between said right and left pairs of screws with all of said gear means in mesh.

8. In a gill box, an upper set of faller bar translating means, said upper set comprising right and left pairs of lead and return screws, first gear means between each pair of screws, said first gear means including adjustment means for providing precise adjustment between the individual screws of each pair, a similarly arranged lower set of faller bar translating means including adjustment means between each pair of screws, second gear means for gearing together the right upper and lower pairs of screws and the left upper and lower pairs of screws, said second gear means comprising adjustment means for providing precise adjustment between the associated upper and lower pairs of screws, said first gear and adjustment means comprising separable gear and gear hub elements on each screw, means for establishing a driving connection between one gear element and its hub element comprising a projection on one element and a plurality of angularly disposed, equally-spaced, projection-receiving recesses on the other element, there being a unit difference angle between the angle included by adjacent recesses and that included by spaced gear teeth, the product of said unit difference angle and the number of recesses being substantially equal to the angle between adjacent gear teeth.

9. In a gill box, an upper set of faller bar translating means, said upper set comprising right and left pairs of lead and return screws, first gear means between each pair of screws, said first gear means including adjustment means for providing precise adjustment between the individual screws of each pair, a similarly arranged lower set of faller bar translating means including adjustment means between each pair of screws, second gear means for gearing together the right upper and lower pairs of screws and the left upper and lower pairs of screws, said second gear means comprising adjustment means for providing precise adjustment between the associated upper and lower pairs of screws, said first and second gear and adjustment means comprising separable gear and gear hub elements on one of said upper screws and the corresponding lower screw of each set, means for establishing a driving connection between each gear element and its hub element comprising a projection on one element and a plurality of angularly disposed, equally-spaced, projection-receiving recesses on the other element, there being a unit difference angle between the angle included by adjacent recesses and that included by spaced gear teeth, the product of said unit difference angle and the number of recesses being substantially equal to the angle between adjacent gear teeth.

angle and the number of recesses being substantially equal to the angle between adjacent gear teeth, there being a second unit difference angle between the angles included by adjacent recesses in each of said two sets of recesses, the product of said second unit difference angle and the number of recesses in one pair of elements substantially equaling said first unit difference angle.

10. In a gill box, an upper set of faller bar translating means, said upper set comprising right and left pairs of lead and return screws, first gear means between each pair of screws, said first gear means including adjustment means for providing precise adjustment between the individual screws of each pair, a similarly arranged lower set of faller bar translating means including adjustment means between each pair of screws, second gear means for gearing together the right upper and lower pairs of screws and the left upper and lower pairs of screws, said second gear means comprising adjustment means for providing precise adjustment between the associated upper and lower pairs of screws, said first and second gear and adjustment means comprising separable gear and gear hub elements on one 25 of said upper screws and the corresponding lower screw of each set, means for establishing a driving connection between each gear element and its hub element comprising a projection on one element and a plurality of angularly disposed, equally-spaced, projection-receiving re-
